UNITED STATES PATENT OFFICE.

LOUIS COHN, OF NEW YORK, N. Y.

DOUBLE CARD-CASE.

1,093,315.

Specification of Letters Patent. Patented Apr. 14, 1914.

Application filed January 17, 1914. Serial No. 812,620.

To all whom it may concern:

Be it known that I, LOUIS COHN, a citizen of the United States, and a resident of New York, borough of Manhattan, in the county 5 of New York and State of New York, have made and invented certain new and useful Improvements in Double Card-Cases, of which the following is a specification.

My invention relates to an improvement 10 in card cases, such, for instance, as are employed for receiving and retaining an identification or pass card of a lodge or organization, the object being to provide an article of this kind which, when opened to its full extent, will present the card in its entirety, that is, when the case is fully opened, the card will be fully opened or unfolded, the case itself being approximately, or slightly larger, in size than that of the card intended 15 to be contained therein. Card cases of this kind have usually been made or constructed in such a way that in order to contain the card or certificate the latter must be folded once, or more times, upon itself before the 20 case can be closed, necessitating the unfolding of the card after the case itself has been opened. As will be hereafter seen, I have constructed my improved case in such way that the card lies flat within the same when 25 30 said case is open, the card, however, with a portion of the case, being folded and completely and wholly contained within the two outer sections. This case, so constructed, is illustrated in the accompanying drawings, 35 wherein—

Figure 1 is a view in side elevation of the case in its folded or closed adjustment. Fig. 2 is a view of the same in its opened adjustment. Fig. 3 is a similar view showing the 40 opened case containing a card or certificate. Fig. 4 is a sectional view taken on the line 4—4 of Fig. 1, and containing a card. Fig. 5 is a sectional view taken on the line 5—5 of Fig. 3.

45 Referring to the drawing, it will be seen that my improved card case comprises four hinged sections 6, 7, 8, 9, the two inner sections 7 and 8 being preferably made of open-work, or of other fanciful design, and 50 slightly less in length and width than the two outer sections 6 and 9, in order that the same may be completely inclosed within the outer sections when the case is in its folded or closed adjustment as illustrated in Figs. 55 1 and 4. On the outer free edges of the outer sections 6 and 9 are provided the narrow

bezels 10 and 11, under which the ends of the card 12 are adapted to fit as illustrated in Figs. 4 and 5, these bezels 10, 11 being of such width as to permit the inner sections 7 and 8 to be folded within the outer sections 6 and 9, without interfering therewith. The inner sections 7 and 8 are hinged together at their adjacent edges as illustrated at 13, the outer edges of these sections being hinged to 60 the inner edges of the outer sections 6 and 9, as illustrated at 14 and 15, this construction and arrangement of the parts permitting the inner sections 7 and 8 to be folded inwardly, and when the case is closed to be contained 65 within and between the sections 6 and 9. From the edges of the outer sections extend the holding clips or fingers 16, these holding clips being employed for the purpose of assisting the bezels 10, 11 in retaining the card 70 within the case as clearly illustrated in Fig. 5, said clips being preferably bent downwardly toward the inner surface or sides of the sections 6 and 9. To accommodate these 75 clips, and in order to prevent the interference of the same with the inner sections 7 and 8 when the case is in its folded adjustment, I form in the ends of the latter the recesses 17 as illustrated in Fig. 2, said recesses allowing the clips and portions of the card 80 to enter therein and thus permit the proper 85 folding of the case.

It will of course be understood that while I have illustrated the inner sections 7 and 8 as being made of open or scroll work, they 90 may be made solid or continuous as are the outer sections 6 and 9, and, furthermore, that while this case has been particularly designed to receive and contain a card of such size as to be open or flat when the case is 95 open, yet there may be used or employed therewith a card of such size as to be folded once or more times upon itself before the case is folded and closed.

For the purpose of retaining the case in 100 its closed or folded adjustment, I form on, or secure, to the edges of one of the outer sections, for instance, section 6, the lugs or projections 18, which, when the case is folded, project over and upon the corresponding 105 edges of the other outer section 9, and impinging thereon, operate to prevent the case from accidentally opening. In order, however, to facilitate the opening of the case when desired, I form on, or secure to, the 110 ends of the outer section, the knobs 19 which, when separated or forced in a direc-

tion away from each other, will operate to open or separate the outer sections.

What I claim is:—

- 5 1. A card case of the character described comprising four sections joined at their adjacent edges, the two inner sections being adapted to be folded and bent within the outer sections when the case is in its closed adjustment.
- 10 2. A card case of the character described, comprising four sections hinged at their adjacent edges, the two inner sections being of slightly less length and width than the two outer sections, the said two inner sections being adapted to be folded and contained within the outer sections when the case is in its closed adjustment.
- 15 3. A card case of the character described comprising four sections hinged at their adjacent edges, each of the outer sections being provided on their ends with a bezel of such width as not to interfere with the folded inner sections when the case is closed, said two inner sections being adapted to be
- 20 25 4. A card case of the character described comprising four sections, hinged together at their adjacent edges, the outer sections being provided on their ends with retaining clips, the two inner sections being provided on their edges with recesses to accommodate said clips when the case is in its closed or folded adjustment.
- 30 5. A card case of the character described comprising four sections, hinged together at their adjacent edges, each of the outer sections being provided with a bezel and with retaining clips, the two inner sections being provided with recesses to accommodate said clips and being slightly less in length and width than the two outer sections, whereby to be wholly contained within said outer sections when the case is closed.

Signed at New York, borough of Manhattan, in the county of New York and State of New York, this 14th day of January, A. D. 1914.

LOUIS COHN.
